TOOTH BRUSH

John Clifford Johnson, Glen Cove, and George H. Nenning, Bellmore, N. Y.

Application December 5, 1935, Serial No. 52,942

5 Claims. (Cl. 15—167)

Our invention relates to toothbrushes and especially to a collapsible variety, the bristles or other cleansing means being impregnated with a tooth powder, paste or like material before being folded and encased within a cellophane envelope.

The main object of our invention is to provide a suitable toothbrush that is simple in its construction, neat in its appearance, efficient for its purpose, and is capable of taking up as little space as possible.

Another object of our invention is to provide a sanitary toothbrush that is capable of being folded up so as to reduce it to the smallest possible size for carrying purposes, and at the same time when unfolded is capable of accomplishing its function in every particular, yet keeping the cost nominal, permitting the user to throw the same away after use.

A further object is to provide such an article in a suitable and compact size that one or more may be conveniently put in the vest pocket, or in a ladies' pocketbook ready for instant use.

A still further object is to provide such article with either bristles or sponge or like means and to saturate with either toothpowder or paste, before being folded, after which it is slid within the cellophane envelope. The article is not only held compact but at the same time is kept sanitary, preventing the escape of the cleansing material applied to the bristles or other substances that may be used.

With the principal objects set forth as above, and others which will appear as the description unfolds itself, reference is made to the following detail description, appended claims and the accompanying drawing, forming a part of this application and in which:

Fig. 1 is a top plan view of the handle, showing the recess for the bristles, sponge or other like material, the central hinge part and the cover and locking member;

Fig. 2 is a like view showing the sponge applied in its dished like section.

Fig. 3 is a longitudinal sectional view showing the relation of the parts.

Fig. 4 is a side view of the toothbrush showing it folded ready to be inserted within a transparent envelope.

Fig. 5 is a top plan view of the toothbrush after it has been inserted within the envelope ready to be packed for shipment, and

Fig. 6 shows a bristle section ready to be applied to the handle.

Referring to the drawing, wherein like characters of reference which designate like parts

throughout the several views, 10 designates the toothbrush handle, which we prefer to make of a stiff fibrous paper, the handle being stamped out and shaped at the same time; and 11 designates the portion for the reception of the bristles. 5 The part 12 is preferably flat to afford a suitable folding place, while the other end is provided with another dished shaped part 13, which terminates in a flat portion tapering to a point 14 at its end as shown. At the other end of the 10 handle we provide a slightly turned up lip 15 with a perforation 16 which receives the point 14 and holds the device in compact form when folded. The part 13 may have its longitudinal 15 sides slightly turned up or dish shaped as at 17, so as to assist in retaining the cleansing powder or paste therein. Intermediate the parts 11, 12 and 13, parts 18 and 19 are made trough-like, so as to reinforce and hold the handle rigid.

It is proposed to make the handle of stiff 20 paper and after it has been shaped, to subject the same to a suitable waterproofing process whereby the paper will be made impervious to water, thereby affording a very suitable and durable handle which will answer every requirement for the function for which it was designed.

The toothbrush illustrated and described herein is an improvement on the toothbrush shown in our previous Patent No. 1,894,413, granted January 17, 1933, and to that extent is a continuation of the same. This style was found unprofitable from the fact that it had to be made in so many different sizes, for the various people who would use them, whereas, with our present form, the toothbrush may be used by young and old alike. For instance, our toothbrush may be placed in the guest room, hotel, club, homes, hospitals, steamships, etc., and may be carried by the ladies in their pocketbooks for use after lunch, at restaurants, in Pullman cars; in fact it will be ready for instant use at any time or place, and the cost so small that the user may throw it away after use. An important feature is that each and every article has enough tooth powder or tooth paste impregnated in the bristles or sponge material for normal use.

Referring now to Fig. 2, this shows a plan view of a form of our toothbrush wherein a sponge 19 is used. In this form, we prefer to provide a slight channel 20 down the center, for an additional supply of the powder or paste. The other end 13 when folded over or the sponge 19 (or bristles 21) holds the powder or paste therein, as shown in Fig. 4, and any small particles that may fall away from the brush after it has

been folded and placed in the cellophane envelope 23, may be retrieved when the toothbrush has been opened up for use, the particles from the envelope may be replaced, thus further providing not only a suitable collapsible toothbrush but at the same time a handy sanitary and convenient one to carry and have ready for instant use.

Of course, with the use of sponge or other like material for cleaning the teeth, the same will be made secure to the section 11, while, if bristles 21 are used, the bristles are first inserted in a suitable base 22, and then the base made secure in the section 11. It is proposed to provide both kinds, that is with bristles, and with sponge, as it is highly desirable with some people to use a stiff bristle, while others prefer the sponge. Children in particular, demand a milder brush as it is not so liable to hurt their gums, and it is believed it will appeal to them to use the toothbrush more often.

When it is desired to use one of our toothbrushes, the envelope is opened at one end and the brush extracted therefrom, then the point 14 is released from the catch 16 and the handle straightened out about the hinge 12, thus providing a straight, stiff handle for use against the teeth. As has been noted, a sufficient supply of powder or paste having been previously placed on and between the bristles or sponge as well as having some spread on the top thereof, there is a bountiful supply for the desired purpose. However, it may be found advantageously convenient to provide an extra supply in the cover portion 13 of our handle which thus not only protects what was impregnated in the bristles or sponge but also provides a receptacle for additional quantities.

In accordance with the provisions of the patent statutes, we have herein described the principal form of our invention, which we now consider to present the best embodiment thereof; but we desire to have it understood that the design of the handle is only illustrative as the handle may be shaped in any other desirable way for the particular purpose; it may be changed or altered without interfering in any way with the general appearance or performance of the article.

What we claim as new and desire to protect by Letters Patent is:—

1. A foldable toothbrush comprising a flattened one-piece body portion of fibrous material or the like adapted for folding, said body portion being provided with a scored intermediate section at the point of folding thereof, upstanding sides defining receptacles at the ends of said body portion, said receptacles both opening in the same direction when in extended position, one being slightly larger than the other, whereby when folded the body portion of the larger of said receptacles constitutes a cover for the other

receptacle, tooth-cleaning means in the latter, and means on said body portion for locking said toothbrush in folded position.

2. A toothbrush comprising integrally formed sections adapted severally to receive a tooth-cleaning medium and means for applying said medium to the teeth, said first-named section being further adapted to constitute a covering means for the last-named section, means interconnecting said sections and provided with a weakened line intermediate the ends thereof whereby the two sections are folded into superposition, a tooth-cleaning medium in said first-named section and means for applying said medium to the teeth in the other section. 15

3. A foldable toothbrush comprising a pressed paper body portion provided at one end with a brush-receiving pocket, brush means in said pocket, means intermediate the ends of said body portion for locating the position of fold thereof, means at the other end of said body portion adapted to cover said pocket when the body portion is folded over, and means on said body portion for detachably retaining it in folded position, said last named means including a tongue arranged at one end of said body portion and a tongue-receiving and retaining opening at the other end of said body portion, said cover means serving simultaneously as a receptacle for tooth powder or the like. 30

4. A one-piece foldable toothbrush of pressed paper or the like comprising a central body portion substantially U-shaped in cross section, said body portion including a scored, flattened, intermediate section defining the locus of folding, a brush-receiving pocket at one end of said body portion, brush means in said pocket, a tooth paste receiving pocket at the other end of said body portion, tooth paste in said last named pocket, the latter functioning also as a cover for said first-named pocket when the toothbrush is folded, and means adapted to be interconnected when the toothbrush is folded to retain the latter against undesired unfolding. 35

5. A one-piece collapsible pressed paper toothbrush consisting essentially of an applicator section and a handle section, applicator means in said applicator section, said handle section being of such configuration at the end thereof remote from the applicator section as to define a cover portion complementary to said applicator section, said handle being provided with a loopable flat portion so situated with reference to the cover portion that when the handle section is looped over, the cover portion fits snugly over the applicator section, intermediate portions of said handle section being trough-shaped whereby it is rendered substantially rigid. 40
